(57) **CLAIM**

The ornamental design for a rope pet treat, as shown and described.

DESCRIPTION

FIG. 1 is a top, front, right side perspective view of a first embodiment of a rope pet treat according to the new design; FIG. 2 is a front elevation view thereof; FIG. 3 is a back elevation thereof; FIG. 4 is a right side elevation view thereof; FIG. 5 is a left side elevation view thereof; FIG. 6 is a top plan view thereof; FIG. 7 is a bottom view thereof; FIG. 8 is a bottom, front, right side perspective thereof; FIG. 9 is a top, front, right side perspective view of a second embodiment of a rope pet treat according to the new design; FIG. 10 is a front elevation view thereof; FIG. 11 is a back elevation view thereof; FIG. 12 is a right side elevation view thereof; FIG. 13 is a left side elevation view thereof; FIG. 14 is a top plan view thereof; FIG. 15 is a bottom plan view thereof; and, FIG. 16 is a bottom, front, right side perspective view thereof.

The broken lines shown in the drawings illustrate portions of the rope pet treat that form no part of the claimed design. The break lines shown in the middle portion of the rope pet treat in FIGS. 9-11 and 14-16 indicate that the appearance of any portion of the article between the break lines forms no part of the claimed design.

1 Claim, 10 Drawing Sheets
